SHOE RACK

Alfred Leighton Ellis, Atlanta, Ga.

Application April 3, 1946, Serial No. 659,179

1 Claim. (Cl. 5—318)

1

This invention relates to a shoe rack which is adapted to be attached to a bed and support shoes placed therein above the floor out of sight beneath the bed.

An object of this invention is to provide a device of this character that can be attached longitudinally of the bed to the rail and spring thereof or transversely of the bed to the opposite rails thereof.

Another object of the invention is to provide a device that is simple in construction, durable in use, efficient in operation and inexpensive to manufacture.

With the above and other objects and advantages in view the invention consists of the novel details of construction, arrangement and combination of parts, more fully hereinafter described, claimed and illustrated in the accompanying drawing in which:

Figure 1 is a side elevation of a bed having an embodiment of the invention attached thereto longitudinally thereof;

Figure 2 is a sectional view on the line 2—2 of Figure 1;

Figure 3 is the same as Figure 1 with the lever attached transversely of the bed;

Figure 4 is a sectional view on the line 4—4 of Figure 3;

Figure 5 is a plan view of the rack;

Figure 6 is a sectional view on the line 6—6 of Figure 5;

Figure 7 is a sectional view on the line 7—7 of Figure 6 and

Figure 8 is a perspective view partly broken of the rack supporting hook.

Referring more in detail to the drawing the rack 10 comprises side walls 12 and end walls 14 which are secured together in any well known manner to form the rectangular shaped frame on which are secured to the top thereof parallel spaced slats or bars 16.

In Figure 1 the rack 10 is shown attached to the bed 18 longitudinally thereof by hooks 20 which engage the rail 22 of the bed in spaced relation to each other and the side wall 12 of the rack on one side thereof. The other side being supported by the hooks 20 engaging the inner spring 24 of the box spring 26 and the opposite side rail 12 of the rack 10 or as shown in Figure 3 the rack can be suspended transversely of the bed by having all four hooks 20 engaging the side rails 22 of the bed.

The box spring 26 is of a type that has no cover adjacent the lower surface so that the hooks may readily enter the spring structure. The hooks can engage the coils of the spring or they can engage the metal straps by which the individual springs are joined to form the unitary bed spring structure. As shown in Figure 2 the hook is

2

engaging the metal straps joining the springs of the unit.

Thus there has been provided a rack which can be suspended below a bed either transversely or longitudinally thereof. The hooks supporting the rack being of any length desired according to the desires of the user thereof so that the rack is hidden beneath the bed but elevated from the floor.

10 It is believed that the construction and manner of use of the invention will be apparent to those skilled in the art and it is to be understood that changes in the minor details of construction, arrangement and combination of parts may be resorted to provided they fall within the spirit 15 of the invention and the scope of the appended claim.

Having thus described the invention what is claimed as new and desired to be secured by

20 Letters Patent is:
In a device of the character described, the combination of a bed having side rails and a box spring of the type that has no covering on its lower surface, and a rack, having end walls and 25 side walls connected to form a rectangular shaped frame, transverse slats secured to the upper marginal longitudinal edges of said frame, a plurality of approximately S-shaped removable hooks engaged with each corner of the rack for suspending said rack beneath said bed longitudinally thereof by connecting the upper end of each hook at the opposite corners of one side rail and the upper ends of the other two hooks to the lower side of the box spring and the lower end 35 of each hook to the rack.

A. LEIGHTON ELLIS.
